UNITED STATES PATENT OFFICE.

JAKOB EHMANN, OF KEARNY, AND FRANK HENRY STUEBLE, OF NEWARK,
NEW JERSEY.

BAR SEAT OR STOOL.

SPECIFICATION forming part of Letters Patent No. 689,863, dated December 31, 1901.

Application filed October 27, 1900. Serial No. 34,551. (No model.)

To all whom it may concern:

Be it known that we, JAKOB EHMANN, residing at Kearny, in the county of Hudson, and FRANK HENRY STUEBLE, residing at Newark, in the county of Essex, State of New Jersey, citizens of the United States, have invented certain new and useful Improvements in Bar Seats or Stools; and we do hereby declare the following to be a full, clear, and exact description of the invention, such as will enable others skilled in the art to which it appertains to make and use the same, reference being had to the accompanying drawings, and to letters of reference marked thereon, which 15 form a part of this specification.

The object of this invention is to facilitate the adjustment of a seat to enable it to be brought to an elevated and forward position convenient to be sat upon in front of a bar or counter and, when no longer needed, to be lowered and forced back beneath the said bar or counter to a position at which it will not interfere with those standing in front of said bar or obstruct the passage or space thereat 25 and to secure other advantages and results, some of which may be referred to hereinafter in connection with the description of the working parts.

The invention consists in the improved seat 30 for use in front of counters, bars, &c., and in the arrangements and combinations of parts of the same, all substantially as will be hereinafter set forth, and finally embraced in the clauses of the claim.

Referring to the accompanying drawings, in which like letters of reference indicate corresponding parts in each of the several views, Figure 1 is a side elevation of the improved seat in its lowered or normal position. 35 Fig. 2 is a vertical section of the same, the seat being shown raised and drawn forward to be sat upon; and Fig. 3 is a view showing the lower part of the seat in plan and the upper parts partly released from said lower part 40 and turned upside down.

In said drawings, *a* indicates a hollow or tubular leg or standard, flanged at the bottom to rest upon the floor with firmness and adapted to be bolted or otherwise fixed with security, so that when sat upon in the manner 45 hereinafter described the seat will not tilt or

upset, and provided at the top with an inclined head *b*, cast integral with said leg or standard. The said inclined head *b* is shown in plan in Fig. 3 and provides a slideway to 55 receive and guide a sliding section *c*, said section being held thereon in an inclined position, as indicated in Figs. 1 and 2, by a cover *d*, which is fastened to the head by screws *d'* or other means and incloses said section and forms with the head an approximately tubular socket. Said head *b* is open, as at *g*, to 60 permit a passage to a rope or similar connection *e*, by means of which the sliding seat-support *i* *i'* is connected to a weight *f*, lying in 65 the tubular leg, for a purpose to be hereinafter explained. The lower end of the socket or tube formed by the head and cover is closed by an end piece *h*, which serves as a stop for the section *c* and seat-supporting rod, while 70 the upper end of said socket is open to permit the limited withdrawal of the said section and the turned lower end of the said seat-supporting rod *i*. The said seat-supporting rod *i* is bent, the upper part *i'* standing vertical 75 to receive the seat board or plate *j*, while the lower part *i'* is inclined and lies at an obtuse angle to said vertical part and lies telescopically in the section *c*. The sections *c* *i'* are 80 angular in cross-section, or so that they will not turn axially, and the outward longitudinal movements are limited by stops *k*, which engage coöperating stops *k'* to prevent entire withdrawal. When the parts are drawn out, as in Fig. 2, the friction of one part on another 85 prevents a downsliding of the sections and the seat-plate will be held up against the weight of the sitter; but when relieved of this weight and by pushing the seat backward with a gentle uplift the said seat may be lowered and pushed back beneath the projecting bar, where it will not interfere with those 90 standing at said bar.

The backsliding of the parts is facilitated by the weight *f*, attached to the seat-support 95 by the cord or wire *e*, which draws on the lower end of said support and renders the back movement very easy. Thus the slight backward push by a finger will lower the seat-plate. The cord preferably passes over 100 an idle pulley *l*, and slots or grooves *m n* are formed in the sliding parts to provide a pas-

sage for said cord to the part i^2 , to which it is attached.

Having thus described the invention, what we claim as new is—

5 1. The improved seat, comprising a leg or standard a , having a head with inclined slideways or bearings, telescopic seat-plate-supporting sections slidably supported on said slideways or bearings and a seat-plate carried

10 on one of said telescopic sections, substantially as set forth.

2. The improved seat, comprising a leg or standard having a head with an inclined slideway or bearing, telescopic sections adapted

15 to slide in said head, one of said sections being bent and provided at its top with a seat-plate, substantially as set forth.

3. The improved seat comprising a leg or standard having an inclined head, telescopic

20 sections adapted to slide on said head, one

of said sections being provided with a seat-plate, a weight arranged in said leg and a flexible connection between said weight and the seat-plate-supporting section, substantially as set forth. 25

4. The improved seat comprising a leg or standard having an inclined head, and a cover forming a socket with said head, a sliding section c , arranged in said socket, a bent rod arranged in said section c , at its lower end 30 and at its upper end having the seat-plate j , substantially as set forth.

In testimony that we claim the foregoing we have hereunto set our hands this 22d day of October, 1900.

JAKOB EHMANN.

FRANK HENRY STUEBLE.
